UNITED STATES PATENT OFFICE

2,428,743

PITMAN

Arvid E. Roxberg, Minneapolis, Minn.

Application February 8, 1945, Serial No. 576,747

1 Claim. (Cl. 74—584)

1

The present invention relates to new and useful improvements in pitmans adapted for connecting the wrist or crank pin of mowing machines, binders or combines with the sickle or cutter bar thereof.

An important object of the present invention is to provide a pitman of this character adapted for connecting the sickle or cutter bar with the wrist or crank pin of the driving mechanism so that the pitman is free to pivot vertically or horizontally for preventing the strain or breakage thereof when the cutter comes into contact with an obstruction.

Formerly it has been the practice of constructing pitmans of this character of wood which easily becomes broken upon engagement of the cutter with an obstruction.

By reason of my improved pitman construction, the same may now be constructed of metal and composed of pivoted sections normally retained in longitudinal alignment to transform the rotary motion of the drive means of the machine to a reciprocatory motion of the cutter and in which the sections of the pitman are adapted to pivot either vertically or horizontally to prevent bending, distortion or breaking of the parts upon the striking of an obstruction.

A further object of the invention is to provide a pitman of this character of simple and practical construction, which is strong and durable, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view of the pitman adapted for use with old style mowers.

Figure 2 is a fragmentary side elevational view showing the extension provided for new style mowers.

Figure 3 is an edge elevational view of the form of the invention illustrated in Figure 1.

Figure 4 is a longitudinal sectional view taken substantially on the line 4—4 of Figure 3.

Figure 5 is a sectional view taken substantially on the line 5—5 of Figure 3.

Figure 6 is a side elevational view of the center rod of the pitman.

Figure 7 is an enlarged side elevational view of the end section of the pitman of the form of the invention illustrated in Figure 2.

2

Referring now to the drawings in detail, and first with respect to the form of the invention illustrated in Figures 1 and 3 of the drawings, the numeral 5 designates the center section of the pitman rod having reduced threaded ends 6 at each end thereof.

The numeral 7 designates generally the knife end attaching strap which includes an inner section 8 having an internally threaded socket 9 at its inner end adapted for threaded engagement with one end 6 of the center section 5 and having a link 10 pivotally connected to the section 8 at the outer end of the latter by means of a bolt or pin 11.

15 Adjacent ends of the section 8 and link 10 are disposed in overlapping relation and are reduced in thickness, as illustrated in Figure 4 of the drawings and having their opposed faces flattened to permit horizontal swinging movement of the link 10 relative to the section 8.

10 The outer end of the link 10 is pivotally attached to the inner end of the knife end clamping strap 7 by a horizontal pin or bolt 12, the adjacent sections of the link and the strap being disposed in overlapping relation and with their opposed faces flattened, as more clearly shown in Figure 1 of the drawings to permit vertical movement of the strap relative to the link.

25 The strap 7 includes the detachable knife end clamping plate 13 secured to the end of the strap by means of a bolt 14 and by means of which the knife end of the cutter bar may be connected to the strap in the usual manner.

Accordingly, by reason of the vertical pivot pin 30 11 and the horizontal pivot pin 12, the strap 7 may be pivoted either vertically or horizontally to prevent breaking of the rod upon the striking of an obstruction by the cutter.

The inner and outer ends of the link 10 may be maintained in longitudinal alignment with respect to the pitman by means of conventional form of spring-projected balls 15 carried at the outer end of the socket 9 and adapted for seating in a socket or recess 16 in the adjacent end 40 of the link 10 and a similar spring-projected ball 17 carried at the inner end of the strap 7 and adapted for seating in a recess or socket 18 in the adjacent end of the link, as more clearly shown in Figure 4 of the drawings. The balls 45 15 and 17 are of a type for snapping into and out of position in their respective sockets.

Likewise, at the other end of the center section 5 of the pitman is a pitman rod section 19 constructed identical to the section 8 and threaded 50 on the adjacent end of the section 5, and to

which a link 20 is pivotally attached similar to the link 10, but for swinging laterally.

A box end pitman strap 21 is pivotally attached to the outer end of the link 20 in a manner similar to the strap 7, but, for swinging vertically, the strap 21 being adapted for use upon old style mowers.

The ends of the link 21 are releasably secured in longitudinal alignment with the pitman by means of ball and socket members, as previously described with respect to the link 10.

Accordingly, the pitman is adapted for horizontal as well as vertical pivotal movement with respect to the strap 21.

In order to adapt the invention for use in newer type mowers, the strap 21 and link 20 are removed at the box end of the pitman and the straps 7 and 10 removed at the knife end thereof and a strap of the form designated at 22 in Figures 2 and 7 of the drawings is pivotally attached to the ends of the sections 8 and 19, respectively.

The strap 22 includes an enlarged head 23 at its outer end having a ball bearing assembly 24 mounted in an opening thereof, the ball bearing assembly providing a pivotal attaching means at right angles to the pivoted inner end of the strap.

The strap 22 is yieldably maintained in longitudinally aligned position with respect to the pitman by means of a spring-projected ball 25 similar to the links 10 and 20.

It is believed that the details of construction and manner of use of the device will be readily understood from the foregoing without further detailed explanation.

Having thus described the invention, what I claim is:

A pitman comprising a center portion, extensions detachably connected to each end of said center portion, links pivoted at their inner ends to each extension for pivotal movement about right angularly related axes, and attaching straps pivoted to the outer ends of the links for pivotal movement in a direction at right angles to that of their adjacent links, and snap catch means releasably maintaining the straps and links in longitudinal alignment with said center portion and responsive to predetermined pivotal force subjected to the straps to release the catch means.

ARVID E. ROXBERG.
